STATIC ELIMINATOR FOR RADIO RECEIVING SETS

Darnell Asberry Dance, Salem, Ark.

Application February 28, 1947, Serial No. 731,631

6 Claims. (Cl. 201—63)

1

This invention relates to a static eliminator for radio receiving sets.

In the operation of radio receiving sets it is known that static may be substantially eliminated if signal strength will be sacrificed to a limited extent. When the receiving set is located in relatively close proximity to a powerful broadcasting station, the static may be entirely eliminated while holding signal strength at a fair volume. This may be done in several ways. It may, for instance, be done by the introduction of resistance in the filament and plate current supply, which, while reducing the signal strength transmitted by one amplifier stage to the next, also reduces the static or noise level to an even greater degree. This same result may also be accomplished by the introduction of resistance into the antenna circuit. Here again the static or noise level may be relatively reduced while permitting the desired signals to come through in but slightly reduced intensity.

The object of the present invention is to provide a static eliminator for a radio receiving set which may be incorporated in the power supply of the receiving set.

Another object of the present invention is to provide a static eliminator for a radio receiving set which may be incorporated in the antenna circuit of the receiving set.

It is a further object of the present invention to provide a static eliminator in the form of a resistor which is of novel but simple construction.

It is an additional object of the present invention to provide a static eliminator in the form of a resistor which may be manufactured out of inexpensive materials, with few machining operations, and at a relatively low cost.

Still other objects, advantages, and improvements will become apparent from the following specification, taken in connection with the accompanying drawing, in which:

Figure 1 is a central longitudinal sectional view through a dual resistor according to the present invention;

Figure 2 is a cross sectional view on the section line 2—2 of Figure 1, showing in particular the identical and symmetrical constructions of the pile-ups in both sides of the power line;

Figure 3 is an exploded view showing the arrangement of the resistor of the present invention for plugging into the power line of a radio receiving set;

Figure 4 is a central longitudinal sectional view through a single line resistor, the same being 55

intended for introduction into the antenna circuit of a radio receiving set;

Figure 5 is a cross sectional view on the section line 5—5 of Figure 4; and

Figure 6 is a circuit diagram showing the resistor of the present invention incorporated into the antenna circuit of a radio receiving set.

Referring now to the drawings in detail, and to Figure 1 in particular. This figure shows the dual resistor enclosed in a casing 10, the latter being formed of any suitable insulating material, such as "Bakelite," having an integral bottom 11 and a top 12 which may be secured in place in any suitable manner, as by being force fitted in position. A diametral partition 13 extends throughout the length of the casing 10 and divides the latter into two semi-cylindrical compartments for the two pile-ups. Male prongs 14—14 extend through the bottom 11 of the casing and female prongs 15—15 through the top 12, the former having contact flanges on the inner side of the bottom 11 and the latter having rims which are preferably countersunk in suitable recesses in the top 12.

As shown in Figure 3 the dual resistor of the present invention may be plugged into a socket 16 mounted in a wall 17 and a plug 18, having attached thereto a cord 19 extending to the radio receiving set (not shown), may then be plugged into the dual resistor.

An important part of my invention resides in the manner in which the elements heretofore referred to as the pile-ups of the resistor are constructed and assembled. The resistor is constructed in stratified form the successive strata extending angularly to each other and each being composed of elements which in themselves comprise a plurality of connected leaves or sections disposed in spaced angular relationship. The separate stratifications are indicated by 19 and 20 and are similar in that each is composed of strips of thin conductive material folded or pleated upon itself. I form these strips of paper coated on one face with a suitable metallic foil, such as tin or a suitable alloy, which is cemented thereto. When these strips are placed in the container 10 the arrangement is such that the separate folds lie partially open or separated in angular position from each line of pleating. In this way air gaps are formed between the contiguous folds. As shown in Figure 1 the strips 19 are positioned with their planes of thin outer folds approximately parallel to the bottom 11 and the top 12 of the casing, the partially open strips 20 lying at right angles to the strips 19 as shown

in Figure 2. That is with the planes of the folds extending longitudinally of the container. The folded strips 19 at opposite sides of the partition 13 form each end of both pile-ups, abutting at one end the male prongs 14 and at the other end abutting the female prongs 15. From this arrangement it will be apparent that there is contact resistance along the planes of juncture of the contiguous strips 19 and 20.

In the modification illustrated in Figures 4-5, the resistor strips 25-26 are arranged in a single pile-up in a cartridge or container 27. Both ends 28-29 of the container are removable, and the former mentioned male and female prongs 14 and 15 are replaced by conductors 30 and 31 which extend to plates 32 and 33 respectively, on the inner faces of said ends.

Figure 6 shows the resistor of the present invention in circuit with an antenna 34 and a capacitor 35. The static and interference oscillations from other than radio communication sources are usually aperiodic, that is of no definite frequency and they can be tuned out with this circuit.

It will be obvious that changes in the sizes, shape, and relative arrangement of the various parts may be made without departing from the spirit of the invention as defined by the appended claims.

I claim:

1. In a resistor for reducing static interference in radio receiving sets, a hollow holder, a plurality of resistance units therein each comprising a narrow pleated foil ribbon arranged seriatim, alternate units being mutually disposed at right angles to each other and in edge-to-face contact.

2. In a resistor for reducing static interference, in radio receiving sets, a hollow casing, a partition dividing said casing into longitudinal halves, a plurality of resistance units therein each comprising a narrow pleated foil ribbon arranged in seriatim in each half of the casing, alternate units being positioned at right angles and in edge-to-face contact.

3. In a resistor for reducing static interference in radio receiving sets, a hollow holder, a plurality of resistance units arranged seriatim in the holder, each unit comprising a loosely folded strip of laminated material, one of said lamina-

tions being a metallic foil, the alternate units being mutually at right angles to the adjacent units and in edge-to-face contact therewith.

4. In a resistor for reducing static interference in radio receiving sets, a hollow holder, a plurality of resistance units arranged seriatim in the holder, each unit comprising a folded laminated section of foil coated paper, the alternate units being mutually at right angles to the adjacent units and in edge-to-face contact therewith.

5. In a resistor for reducing static interference in radio receiving sets, a cylindrical casing, a partition dividing said casing longitudinally into semi-cylindrical sections, a plurality of resistance units arranged seriatim in each section, each resistance unit comprising a loosely folded laminated foil element, alternate resistance units being positioned longitudinally and other intermediate resistance units being positioned radially of said casing the last mentioned units being in edge-to-edge contact with the faces of adjacent first mentioned units.

6. In a resistor for reducing static interference in radio signal receiving sets, the combination with a hollow casing having circuit terminals at its ends, of a series of resistance units each composed of laminated and pleated foil strips loosely folded and extending with their pleats crosswise of the casing and in spaced relation in the casing, those at the ends contacting said terminals, other similar formed units extending with their folds disposed longitudinally of the casing and interposed between the first mentioned units and contacting them edgewise.
